INVENTOR
LOUIS N. D. WILLIAMS
BY HIS ATTORNEY
Harry Smith

UNITED STATES PATENT OFFICE.

LOUIS N. D. WILLIAMS, OF OGONTZ, PENNSYLVANIA.

STITCH TRANSFERRING AND DOUBLING DEVICE.

1,203,949.

Specification of Letters Patent.

Patented Nov. 7, 1916.

Application filed January 27, 1916. Serial No. 74,566.

To all whom it may concern:

Be it known that I, LOUIS N. D. WILLIAMS, a citizen of the United States, residing in Ogontz, Pennsylvania, have invented 5 certain Improvements in Stitch Transferring and Doubling Devices, of which the following is a specification.

My invention relates to a stitch transferring and doubling device for use in carrying out that method of closing the end of a tubular web which consists in engaging 10 stitches around the end of the web by a set of transfer points, doubling one-half of these points over into register with the other 15 half, doubling the stitches on one-half of the points, and then uniting these double stitches, the object of my invention being to prevent dulling or burring of the ends of the points by contact with one another when 20 they are folded over into registry with one another. This object I attain in the manner hereinafter set forth, reference being had to the accompanying drawing, in which—

25 Figure 1 is a transverse sectional view of a transfer point structure made in accordance with my invention, showing the parts of the same in the position occupied by them when transferring the web from the machine upon which it was produced; Fig. 2 is a similar section showing the parts adjusted in position for doubling the stitches on one-half of the points; Fig. 3 is a top view of the device with the parts in the 30 position shown in Fig. 1 and without the web upon the points, and Fig. 4 is a transverse section illustrating a modified construction.

35 In the drawing, I have shown the transfer point structure as designed for removing the web from the needles of a circular knitting machine, although my invention is not limited thereto but is equally available for use in connection with machines of other 40 types.

45 In the drawing, 1—1^a represent two semi-circular sets of transfer points, the carrier therefor comprising two semi-circular members 2—2^a so as to permit adjustment of the 50 points so that all project in the same direction, as shown in Fig. 1, for application to the stitches of the web on the machine, or so that one-half may be turned over the other half and the points caused to register

55 with one another, one half projecting in a direction opposite to that of the other half, as shown in Fig. 2, for the purpose of doubling stitches upon one set of points, the point carrier for this purpose being applied to a hinged structure such for instance as that shown in my application for 60 patent filed January 20th, 1916, Serial No. 73,116.

65 My present invention consists in disposing the transfer points 1^a in a different plane from that of the transfer points 1, so that when the parts are in the position shown in Fig. 2 the ends of the points will not contact with one another and the risk of dulling or burring these points by reason of 70 such contact will therefore be avoided.

75 In applying the point ring to the web upon the machine the points 1 will engage stitches of one course and the points 1^a will engage stitches of an adjoining course, and when the points 1^a are doubled over into 80 register with the points 1 said points 1^a will, when the stitches upon the points 1 are stripped therefrom as by means of the stripper 3, Fig. 2, be caused to engage with the remaining stitches of the course whose other stitches were originally engaged by said 85 points 1^a or with the stitches of a course adjacent thereto, the points 1^a, with the doubled stitches upon them, being then restored to their original position and the point carrier applied to a looping machine 90 whereby the doubled stitches upon the points 1^a can be united, the course of stitches comprising those originally engaged by the points 1 being first raveled out if desired.

95 The transfer points and the stitches of the web are, for ease of illustration, shown as of a much coarser gage than they would be in practice.

When the points of one set are in the form of pins and those of the other set are grooved or channeled, as shown in Fig. 4, the pins may enter said grooves or channels as there illustrated when the points are adjusted so as to cause those of one set to register with those of the other set.

I claim:—

1. A stitch transferring device comprising 105 two sets of stitch engaging points, and carriers therefor, one of which can be folded over the other, the points being so disposed in said carriers that when one of the latter

is so folded over the other the points will be in different longitudinal planes.

2. A stitch transferring device comprising two semi-annularly disposed sets of stitch 5 engaging points one of longer radius than the other, and two semi-annular carriers for said points one of which can be folded over the other.

In testimony whereof, I have signed my name to this specification, in the presence of 10 two subscribing witnesses.

LOUIS N. D. WILLIAMS.
